WOOD TANK CONSTRUCTION

Gwynne Raymond and Lee E. Young, Oklahoma City, Okla., assignors to Black, Sivalls & Bryson, Inc., Oklahoma City, Okla., a corporation of Maine

Application August 29, 1936, Serial No. 98,526

4 Claims. (Cl. 217—97)

This invention relates to tanks and similar containers particularly constructed of wood staves bound together with hoops. When a container of this character is full of liquid the wood swells and the joints become tight but when the staves dry out, as they do when the liquid is low, the wood shrinks and the joints open with the result that the tank leaks. This shrinkage requires frequent tightening of the hoops and occasional coopering in order that the tank may be kept in serviceable condition. This difficulty is especially troublesome during long seasons of drouth and high temperature. In cases where an ample water supply is available, such tanks may be kept serviceable by running a stream of water over the exterior of the deck and sides of the tank, but in many cases where wood tanks are employed, particularly in the oil fields, the region is dry and arid and water is scarce and expensive.

It is, therefore, the principal object of the present invention to provide a wooden container construction wherein the wood is kept permeated with water or other fluid supplied by means of interior grooves or passages incorporated in construction of the container.

Other important objects of the invention are to provide a simple and inexpensive construction forming the channels and passageways so that the cost of the tank is not increased materially over that of an ordinary wooden container.

It is also an important object of the present invention to provide a conservative supply of liquid for automatically retaining the channels and passageways in filled condition.

In accomplishing these and other objects of the invention, as hereinafter pointed out, we have provided improved details of structure, the preferred form of which is illustrated in the accompanying drawings, wherein:

Fig. 1 is a perspective view of a container, such as an oil storage tank, embodying the features of the present invention, a portion of the side wall being broken away to illustrate the channels or passageways for containing the permeating liquid.

Fig. 2 is a plan view of the tank, a part of the head or deck and wall being shown in section to better illustrate the channels or passageways for the permeating liquid.

Fig. 3 is an enlarged detail section through the deck of the tank, particularly illustrating the connection between the storage receptacle carrying the permeating liquid and the tank passageways.

Fig. 4 is a detail section through a portion of the side wall of the tank particularly illustrating the inlet connection wherethrough the passageways and storage receptacle are filled with permeating liquid.

Fig. 5 is an enlarged detail perspective view of one of the staves composing the side wall of the tank.

Fig. 6 is a section through the stave on the line 6—6 of Fig. 5 illustrating a transverse bore 10 therein which cooperates with similar bores in the other staves to form an annular passageway connecting the vertical ways in the sides of the staves.

Fig. 7 is an enlarged detail view through the upper portion of the tank particularly illustrating the connection of the horizontal grooves in the deck with the vertical grooves in the sides of the staves through an annular passageway formed in the croze of the staves.

Fig. 8 is a section on the line 8—8 of Fig. 7.

Fig. 9 is a perspective view of one end of one of the deck boards part of which is broken away to illustrate one of the transverse grooves.

Referring more in detail to the drawings:

1 designates a tank, or container, such as used in oil fields for storing oils or other liquids which are ordinarily corrosive to metal structures. For this reason the tank is constructed of wood and includes an annular wall formed of a plurality of vertical staves 2 and having croze grooves 3 and 4 at their upper and lower ends to engage the peripheral edges of the tank deck and bottom 5 and 6 respectively.

The deck 5 and bottom 6 are circular disks formed of juxtaposed boards 7 arranged in edge to edge contact and having their ends extending into the croze grooves. The wooden parts thus described are bound together by hoops 8 encircling the wall of the tank as in conventional wooden tank construction. The tank decks are also usually reinforced by suitable transverse beams 9, 10 and 11 as shown in Figs. 1 and 2, and the decks are braced by internal shoring 40 (not shown).

Tanks constructed as above described are kept liquid-tight by coopering and tightening the hoops, however, when the tank is used in hot, arid climates the wood is subject to so much shrinkage that it is difficult to keep the tank from leaking.

In accordance with the present invention we construct the tank with a series of channels or passageways that are kept full of liquid to 55

permeate the wood and prevent shrinkage as now to be described.

An abutting edge 12 of each stave is provided with a longitudinal groove 13 at a point substantially midway between the inner and outer faces 14 and 15 of the staves. The grooves 13 do not extend the entire length of the staves but the upper ends 16 terminate in substantial alignment with the upper edges of the croze grooves 3 while the lower ends 17 terminate a short distance above the lower croze grooves 4, as clearly shown in Fig. 5.

Extending transversely through the staves from the edge faces 12 to the opposite edges at the lower terminals of the grooves 13 are horizontal bores 18 which cooperate to form an annular passageway 19 completely encircling the tank and which forms a manifold connected with the lower ends of all of the grooves 13. The croze grooves 3 at the upper ends of the staves are provided with counter grooves or ways 20 that are cut in the bottom faces thereof and of less width to provide stop shoulders on the respective sides of the croze grooves to be engaged by the peripheral edge of the deck 5, as shown in Fig. 5. The staves at the ends of the counter grooves 20 are notched as at 21, on the edges having the vertical grooves 13, to provide communication between the vertical grooves 13 and the counter grooves 20. The counter groove 20 of one stave cooperates with the counter groove of the other staves to form an upper annular passage 22 extending completely around the tank within the planes of the inner and outer surfaces of the upper deck to form a manifold interconnecting the upper ends of all of the vertical grooves 13.

The boards 7 composing the upper deck also have one of their side edges 23 provided with a longitudinal groove 24 having the ends thereof communicating with the counter grooves 20. The grooves 24 are also interconnected by means of transverse bores 26 and 27 extending transversely through the boards, as best shown in Figs. 2 and 7, the transverse bores being located in registering alignment and in the plane of the horizontal grooves 24 to provide cross channels connecting all of the grooves 24.

When the staves are assembled in the form of a tank, the smooth side edge 28 of one stave closes the open side of the grooves 13 to form closed channels. Likewise the smooth side edges 29 of the boards comprising the upper deck cover the open sides of the grooves 24 to form closed horizontal channels for containing a permeating liquid, such as water, that is admitted to the passageways through an inlet fitting 30 carried in one of the staves and intersecting the horizontal bore 18 thereof.

The inlet fitting is pressed into an opening 31 extending through the face sides of one of the staves, as best shown in Fig. 4, and has a head 32 on its inner end that forms an annular stop shoulder 33 adapted to sealingly engage against the inner face of the stave. The opposite end 34 of the fitting projects from the outer face of the stave and carries a washer 35 sleeved thereover and retained in sealing engagement with the tank by means of a nut 36 threaded on the projecting end of the fitting and having a feathered edge 37 wedgingly engaging in a groove 38 formed between the fitting and the inner diameter of the washer, as best shown in Fig. 4. When the nut 36 is tightened the head and washer of the fitting are drawn into sealing contact with the inner and outer faces of the stave.

The sleeve portion of the fitting is provided at its projecting end with internal threads 39 to mount a nipple 40 carrying a valve 41 adapted to be opened and closed by a hand wheel 42. The opposite side of the valve is connected with a supply pipe 43 by which the passageways or channels of the tank are filled with liquid when the valve is opened as later described.

The opposite side of the fitting is also internally threaded to receive a plug 44. The outer periphery of the tube portion of the fitting which extends through the opening 31 is provided with an annular recess 45 forming an annular passageway connecting the horizontal circumferential passageway with openings 46 formed in the wall 15 of the fitting so that the liquid admitted through the valve may flow through the opening 46 and around the recess 45 into the passageway 19.

Mounted on the cross beams of the upper deck, at a point adjacent one end thereof, are spaced cross sills 47 and 48 for supporting a storage receptacle 49. The storage receptacle 49 is shown of cylindrical form and has its lower end provided with angle shaped legs 50 which are secured to the cross sills 47 and 48 by bolts 51. The receptacle 49 includes a cylindrical wall 52 having a closed bottom 53 and an open top normally closed by a cover 54, the cover being provided with an air hole 55 through which air may pass into and out of the receptacle with the rise and fall 30 of the liquid therein.

The receptacle 49 is provided with an outlet fitting 56 that is connected with a tubular fitting 57 identical to the tubular fitting previously described, and which is pressed into an opening 58 35 that is formed in transverse axial relation with one of the horizontal grooves 24 as best shown in Fig. 3. The projecting threaded end of the fitting extends from the upper face of the deck and connects with a nipple 59, having an L 60 40 carrying a nipple 61. The nipple 61 also has an L 62 on its opposite end that connects with a horizontal pipe 63 having an L 64 carrying a nipple 65 connected with an L 66 on a pipe 67 that connects with the receptacle fitting 56 through a 45 union 68. The elbow connections between the pipes and nipples provide for expansion and contraction and facilitate connection of the receptacle 49.

Attention is here directed to the fact that since 50 water will not soak far into the fibres of wood, the staves composing the side wall and the boards comprising the upper deck are made relatively narrow so that water contained in the respective passageways may permeate entirely 55 through the wood. The roof deck of the tank may be provided with an expansion dome and thief hole 69 and 70 respectively.

The tank, after being assembled, preferably has its roof deck covered with a layer of insulation 71 60 such as sand, gravel, dirt or the like, so as to prevent excessive evaporation of the water contained in the passageways therein.

In filling the passageways of a tank constructed and assembled as described, the valve 41 is opened 65 to allow flow of liquid under pressure into the inlet fitting 30 and through the ports 46 and into the annular passageway 19 formed at the lower ends of the staves. The water will be distributed uniformly to all of the vertical passageways 13 70 and will rise therein to flow into the annular passageway formed at the bottom of the usual croze grooves 3. From this passageway the water will be distributed to the transverse passages 24 and through the intersecting bores 26 and 27 to fill 75

all of the grooves. The water will then flow through the fitting 57 and from the fitting to the storage receptacle 49. During filling of the system the air therein is pushed ahead of the water and discharged through the opening 55 in the cover 54 of the receptacle. When the system, including the receptacle 49, is filled, the valve 41 is closed.

The water contained in the channels or passageways is absorbed by the pores of the wood to effect swelling of the wood staves and deck boards for maintaining the joints of the tank in tight condition. As the liquid permeates into the wood the hydraulic pressure contained in the supply tank keeps the passageways in filled condition. When the storage receptacle becomes empty it may be refilled by opening of the valve 41, as previously described.

From the foregoing, it is obvious that we have provided a tank having a passageway system for containing permeating liquid which is of simple and inexpensive construction and that adequately supplies the permeating liquid to all parts of the tank which are subject to shrinkage incidental to dry and arid conditions surrounding the tank.

What we claim and desire to secure by Letters Patent is:

1. A wood tank including a side wall formed of staves each having crozes formed across its inner face adjacent the ends thereof, a groove extending in one edge from the upper croze toward the lower croze for forming vertical passageways between the respective staves, and a counter groove formed in the bottom of the upper croze and having connection with the edge groove; deck and bottom members engaged in said crozes with the peripheral edge of the deck member closing the croze side of the counter grooves whereby the counter grooves cooperate to form an annular passageway encircling the tank circumferentially of the upper crozes through which the vertical passageways are supplied with a permeating liquid, and means for supplying a permeating liquid to the passageways.

2. A wood tank including a side wall formed of staves each having crozes formed across its inner face adjacent the ends thereof, a groove extending in one edge from the upper croze toward the lower croze for forming vertical passageways between the respective staves, and a counter groove formed in the bottom of the upper croze and having connection with the edge groove; deck and bottom members engaged in said crozes with the peripheral edge of the deck member closing the

croze side of the counter grooves whereby the counter grooves cooperate to form an annular passageway encircling the tank circumferentially of the upper crozes through which the vertical passageways are supplied with a permeating liquid, said staves having transverse bores connected with the lower ends of the vertical passageways, and means for supplying a permeating liquid to said passageways.

3. A wood tank including a side wall formed of staves each having crozes formed across its inner face adjacent the ends thereof, a groove extending in one edge from the upper croze toward the lower croze for forming vertical passageways between the respective staves, and a counter groove formed in the bottom of the upper croze of less width than said croze to form a stop shoulder, said counter grooves being connected with the edge groove; deck and bottom members engaged in said crozes with the peripheral edge of the deck member abutting against the stop shoulder to close the croze side of said counter grooves whereby said counter grooves form an annular passageway encircling the tank circumferentially of the upper crozes through which a permeating liquid is supplied to the vertical passageways for permeating said staves; and means for supplying a permeating liquid to the annular passageway.

4. A wood tank including a side wall formed of staves each having crozes formed across its inner face adjacent the ends thereof, a groove extending in one edge from the upper croze toward the lower croze for forming vertical passageways between the respective staves, and a counter groove formed in the bottom of the upper croze of less width than said croze to form a stop shoulder, said counter grooves being connected with the edge groove; deck and bottom members engaged in said crozes with the peripheral edge of the deck member abutting against the stop shoulder to close the croze side of said counter grooves whereby said counter grooves form an annular passageway encircling the tank circumferentially of the upper crozes through which a permeating liquid is supplied to the vertical passageways for permeating said staves, said deck member being formed of a plurality of staves each having an edge groove extending longitudinally thereof and registering at the ends with the counter grooves to form passageways connected with the annular passageways; and means supplying a permeating liquid to said passageways.

GWYNNE RAYMOND.
